INVENTOR
BY Victor J. Evans

ATTORNEY

UNITED STATES PATENT OFFICE.

WESLEY N. COLEMAN, OF JACKSONVILLE, FLORIDA.

COMBINATION CASE.

Application filed September 8, 1923. Serial No. 661,663.

To all whom it may concern:

Be it known that I, WESLEY N. COLEMAN, a citizen of the United States, residing at Jacksonville, in the county of Duval and State of Florida, have invented new and useful Improvements in Combination Cases, of which the following is a specification.

This invention relates to an improved case for holding cigarettes and matches, the general object of the invention being to provide means for thoroughly protecting the cigarettes and matches from dampness and from being crushed.

Another object of the invention is to so form the case that the cigarettes can be placed therein without removing them from their original package.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of the complete case with parts broken away.

Figure 2 is an edge view with the cover removed.

Figure 3 is a perspective view of the case with the cover lifted.

In these views, 1 indicates the case and 2 the cover thereof, which overlaps the upper part of the case and extends well down the same so as to cover the match scratching surface 3 on one end of the case. The sides of the case are cut away to provide the recesses 4 at the top thereof and one end is cut away to provide the recess 5 at the top thereof, these recesses facilitating the removal of the matches and cigarettes from the case. A partition 6 divides the case into a chamber

7 for holding the cigarettes and a chamber 8 for holding matches, the chamber 8 being provided with a bottom 9 which is well above the bottom of the case. 50

The package containing the cigarettes is adapted to be placed in the chamber 7, the projecting end 10 at the top of the case and the partition 6 forming a grip for the package. It is of course understood that the top 55 of the package is removed so that the cigarettes can be removed therefrom after the package has been put in place. The overlapping top thoroughly protects the cigarettes and the matches and also the striking 60 surface and this top can be used as an ash tray when necessary. As will be seen there are no springs or hinges to get out of order and to take up room.

It is thought from the foregoing description that the advantages and novel features of my invention will be readily apparent.

I desire it to be understood that I may make changes in the construction and in the combination and arrangement of the several 70 parts, provided that such changes fall within the scope of the appended claim.

What I claim is:—

A case of the class described comprising a body having a partition therein dividing the 75 same into a cigarette chamber and match chamber, the upper edges of the side walls of the first chamber being recessed, the recesses terminating at the partition and a slight distance from the end of the case so 80 that this end is of channel shape in cross section to form with the partition a grip for a package of cigarettes, the end of the body which forms a portion of the match chamber having a recess in its upper end 85 and a bottom spaced from the bottom of the body and having a roughened portion for forming a striking surface, a top overlapping the body and covering the recesses and the striking surface when in position. 90

In testimony whereof I affix my signature.

WESLEY N. COLEMAN.
